UNITED STATES PATENT OFFICE

143,493

DESIGN FOR A BANDEAU

Charlotte Knudsen, Burlingame, Calif.

Application October 30, 1944, Serial No. 116,042

Term of patent 3½ years

(Cl. D86—10)

To all whom it may concern:

Be it known that I, Charlotte Knudsen, a citizen of the United States of America, and a resident of the city of Burlingame, county of San Mateo, and State of California, have invented a certain new, original, and ornamental Design for a Bandeau, of which the following is a specification, references being had to the accompanying drawing, forming part of this application, in which:

I claim:

The ornamental design for a bandeau, substantially as shown.

CHARLOTTE KNUDSEN.
